UNITED STATES PATENT OFFICE.

WALTER B. GUILD, OF BOSTON, MASSACHUSETTS.

CARD-GRINDING ROLLER.

SPECIFICATION forming part of Letters Patent No. 299,131, dated May 27, 1884.

Application filed October 24, 1883. (No model.)

To all whom it may concern:

Be it known that I, WALTER B. GUILD, a citizen of the United States, residing at Boston, in the county of Suffolk and State of Massachusetts, have invented certain new and useful Improvements in Card-Grinding Rollers; and I do hereby declare that the same are fully described in the following specification, and illustrated in the accompanying drawing.

The object of this invention is to provide an improved card-grinding roller for use with appropriate mechanism for the purpose of sharpening the points of the wire teeth of machine-cards. Various devices have heretofore been employed to accomplish this end, the most successful having a grinder with a reciprocating or traverse motion over the face of the card. Perhaps the most popular device has a grinding-wheel about five inches in diameter and four or five inches face, arranged to rapidly traverse on a shaft the entire width of a card—that is, from thirty to fifty inches—and of course grinding at no time upon more than five inches of surface. In this traverse motion the sides or edges of the wheel press against the sides or edges of the teeth at and near their points, thus grinding the sides as well as the front of the points. It is noticeable that the edges of the wheel are the most effective parts in forming the needle-points desired in card-clothing.

Based on these observations, my improvement consists in a roller extending over and adapted to act on the entire width of the card at once, and having a succession of cylindrical grinding-surfaces separated by a series of independent circumferential grooves, as shown in the drawing, which is a plan of the roller detached from its frame and operating devices. This roller has a slight traverse motion about equal in extent to the width of one of the grinding-surfaces, so that by this short travel all the card-teeth within the range of the entire roller will be acted upon not only by the several cylindrical grinding-surfaces, but also by the walls of the successive grooves acting edge-wise simultaneously on the sides of the card-teeth. The cylindrical grinding-surfaces are shown at A A, and the separating-grooves at B B.

C is the shaft, revolving with the roller in bearings formed in a suitable frame, and having a reciprocating motion imparted to it regularly during its rotation. The grinding material is, by preference, coarse emery, and the cylindrical character of the surfaces A A is essential to the proper shaping of the points of the teeth, as is also the succession of circumferential grooves, the walls of which act with uniform effect on the teeth in both directions of the reciprocating movement, as a spiral groove would not. The function of these grooves is that (the clothing being quite elastic) the points will spring to place with the passage of each groove as the roller reciprocates in its rotation. The edges of each groove act on the sides of the wire points, thus producing with the cylindrical surfaces the needle-points on the teeth. The sides of each groove and the grinding-faces A A act on the teeth precisely as do the sides and face of the single traversing wheel referred to; but instead of such action at a single point, as in that device, my grooved roller is acting in many different places at once, vastly enhancing its efficiency. Thus with the roller shown in the drawing, having ten grooves and eleven cylindrical faces, the effect will be as though eleven wheels were grinding the card and eleven edges were operating to form needle-points continually. These narrow grinding-faces, separated by deep grooves, give opportunity for air-currents to cool the teeth in the intervals of grinding, with the effect of not injuring the temper of the steel teeth now largely used.

I claim as my invention—

The improved card-grinding roller herein described, extending the full width of the card, and consisting of a series of cylindrical grinding-sections, A, separated by independent circumferential grooves B, having the ventilating and edge-grinding capabilities, substantially as set forth.

In testimony whereof I hereto affix my signature in presence of two witnesses.

WALTER B. GUILD.
